FIG.1

FIG.5

FIG.2

FIG.6

FIG.3

FIG.7

FIG.8

FIG.4

FIGURE 1 is a perspective view of a combined liquid dispensing container and cover therefor, showing my new design;

FIGURE 2 is a plan view;

FIGURE 3 is an edge view;

FIGURE 4 is a sectional view taken on the line 4—4 of FIG. 3;

FIGURE 5 is an exploded view showing the cover separated from the container;

FIGURE 6 is a plan view of the container with the cover removed;

FIGURE 7 is a side elevational view with the cover removed; and

FIGURE 8 is an elevation view looking from the right of FIG. 7.

The dominant features of my design reside in the portion shown in full lines.

I claim:

The ornamental design for a combined liquid dispensing container and cover therefor, as shown and described.
